UNITED STATES PATENT OFFICE.

CHARLES H. FIELD, OF PROVIDENCE, RHODE ISLAND.

ENGRAVING-MACHINE.

SPECIFICATION forming part of Letters Patent No. 663,017, dated December 4, 1900.

Application filed March 13, 1899. Serial No. 708,976. (No model.)

To all whom it may concern:

Be it known that I, CHARLES H. FIELD, a citizen of the United States, residing at and whose post-office address is No. 113 Point 5 street, Providence, in the State of Rhode Island, have invented a new and useful Improvement in Engraving-Machines, of which the following is a specification.

My invention relates to machines adapted 10 for engraving the backs of watchcases; and it consists in the improved means for operating the graver-carriage, as hereinafter fully set forth.

In the accompanying drawings, Figure 1 15 represents a top view of the machine for guiding the graver over the protuberant surface of the watch-back. Fig. 2 represents the detail rear view on a diminished scale. Fig. 3 represents a section taken in the line 3 3 of 20 Fig. 1.

In the drawings, A represents a portion of the bed-frame of the machine, to which the graver-carrying mechanism is secured.

B represents the work shaft or spindle, at 25 the end of which the piece of metal to be engraved or ornamented is secured.

The block C for supporting the graver-carriage is secured to the bed of the machine and provided with the traversing screw D, to 30 the outer end of which are secured the hand-crank E and the bevel-gear F, the said bevel-gear being driven by means of the bevel-pinion F', secured to the shaft G, the opposite end of the said shaft being provided with the 35 spur-gear H, from which operative connection is made with the gear I upon the work-spindle B by means of the stationary intermediate gear J, the movable intermediate gear K, pivoted to the bearing-stud J' of the intermediate 40 gear J by means of the bar K', to the outer end of which the gear K is connected by means of the stud K², so that upon the rotation of the work-spindle B the proper traversing movement will be imparted to the graver-carriage L by means of the traversing screw D. The screw D passes through the nut D', secured to the traversing block M, which slides upon the supporting-block C. The graver-carriage N is secured to the traversing block 45 M by means of a vertical pivot O at its front end and the dovetailed slide Q, which is fitted into a recess in the traversing block, so

that said slide may move to and fro in a line at right angles to the axis of the traversing screw. This movement of the slide Q is effected by the movement of the traversing block M, which is due to the revolution of its screw D. Upon the stud m, extending upward from the traversing block, is pivoted the lever R, provided at its outer end with the antifriction-roller n and at the inner end engages with the pin o, extending upward from the slide Q, the said slide being drawn in the outward direction by means of the spiral spring S, attached at one end to the slide and at the other to a bracket p, secured to the traversing block M, and the action of the spring S will serve to hold the roller n in close contact with the curved surface q of the stationary cam-plate P, which represents a curve the reverse of that of the surface of the watch-back. It will be readily seen that the movement to and fro of the traversing block M by means of its traversing screw D will move the antifriction-roller of the lever R along the curved 70 surface q of the stationary cam-plate P, and the engagement of the opposite end of the lever with the pin o will cause the movement of the slide Q in or out in a line at right angles to the path of the traversing block M. The graver-carriage N embraces the pivoted bed-piece a, a tool-post b, a slide c, on which the tool-post is mounted, and a hand-lever d, pivoted to the bed-piece a by means of the overhanging arm e and provided at its inner 75 end with the stud r, from which connection is made by a spiral spring f to the slide c, so that the spring may be controlled for forcing the tool-post forward or so that the slide may be released from the action of the spring when 80 the tool-post is to be withdrawn pending adjustment.

One side of the graver-carriage is provided with the curved arm k, having at its outer end the antifriction-roller g and the attached 85 chain h, which passes over a pulley i and thence downward through the bed of the machine, the said chain being weighted to effect the required turning movement of the graver-carriage N upon its pivot O.

In order that the carriage N shall be turned on its pivot only to a degree which shall be in exact proportion to the traversing movement due to the screw D, the stationary cam-

plate P is so set that its curved edge *j* forms an abutment with which the antifriction-roller *g* engages and along which it cannot be moved by the weight except at a speed corresponding to that at which the carriage is moved toward the cam-plate P by the traversing screw. The cam-plate P is mounted upon a suitable standard which is secured to the bed of the machine.

10 In carrying out my improvement an integral cam-plate P is preferably employed for imparting both the to-and-fro and the pivotal movement to the graver-carriage, so that the cam-surfaces *j* and *q* cannot be thrown out of adjustment with each other, and by my improvement the parts which serve to impart the to-and-fro movement to the graver-carriage are of much simpler construction than heretofore and not liable to derangement by wear.

I claim as my invention—

15 In an engraving-machine, the combination of the traversing block M, the slide Q in the

traversing block, the lever R pivoted to the traversing block and engaging at its outer end with the said slide Q, the stationary guide-surfaces *q* and *j*, means for holding the outer end of the lever R against the guide-surface *q*, the screw D for causing the lateral movement of the traversing block and the movement of the outer end of the lever R along the guide-surface *q*, to impart endwise movement to the slide Q, and the graver-carriage N, pivoted to the slide Q, and provided with the arm *k* adapted to bear against the guide-surface *j*, for changing the direction of the axis of the graver-carriage, whereby the operation of the graver-tool will be regulated from guide-surfaces having a fixed relation to each other, so that they may be advantageously formed upon an integral plate, substantially as described.

CHARLES H. FIELD.
